UNITED STATES PATENT OFFICE.

JOHN M. YOUNG AND CLARENCE M. SYMONDS, OF SAN FRANCISCO, CALIFORNIA, ASSIGNORS TO AMERICAN CAN COMPANY, OF NEW YORK, N. Y., A CORPORATION OF NEW JERSEY.

FRICITION-TOP CAN.

No. 799,821.

Specification of Letters Patent.

Patented Sept. 19, 1905.

Application filed May 10, 1905. Serial No. 259,667.

To all whom it may concern:

Be it known that we, JOHN M. YOUNG and CLARENCE M. SYMONDS, citizens of the United States, residing in San Francisco, in the county 5 of San Francisco and State of California, have invented a new and useful Improvement in Friction-Top Cans, of which the following is a specification.

Our invention relates to improvements in 10 friction-top cans or cans having a top or head with a large opening therein surrounded by a slightly-inclined or wedging annular flange constituting a friction-face and closed by a friction cap or cover having a corresponding 15 slightly-inclined or wedging friction face or flange engaging the friction-face of the can top or head.

The object of our invention is to provide a 20 friction-top can of a simple, durable, and economical construction having, as usual in such cans, a removable cap or cover for opening and closing the can as the contents are being used and provided with a protective frangible seal adapted to bear the name or 25 trade-mark of the manufacturer of the material in the can and which protective seal will require to be broken or destroyed before the can can be opened, and thus guard against the can being again refilled with spurious or 30 inferior goods and palmed off under the original label on the can as genuine, and in which the frangible seal may be applied at the can-factory where the cans are manufactured to a seal-holder ring, adapted to be sealed and 35 irremovably secured to the can after it is filled by a friction-closure similar to that employed for sealing and securing the friction-cover itself in place.

Our invention consists in the means we employ and herein shown and described for practically accomplishing this object or result—that is to say, it consists in a friction-top can having an annular top provided with a large opening therein surrounded by a depending 45 flange, a frangible-seal-carrying friction-fit ring fitting within said annular can-top and provided with a fold embracing a frangible seal, a frangible seal carried by said ring, and a friction top or cover fitting within said ring.

50 It also consists in the novel construction of parts and devices and in the novel combinations of parts and devices herein shown and

described, and specifically set forth in the claims.

In the accompanying drawings, forming a 55 part of this specification, Figure 1 is a vertical sectional view of a can embodying our invention. Fig. 2 is a top or plan view. Fig. 3 is a top or plan view with the friction cap or cover removed, and Fig. 4 is an enlarged 60 sectional view.

In the drawings, A represents the can-body, the same being of any suitable kind or form. B is the friction top or head of the can, having a large opening B' therein surrounded by 65 a depending annular flange b. The annular top or head B has an outer annular seaming-flange b', by which it is united by a seam a of any suitable kind to the can-body A. The seam a, as indicated in the drawings, is a 70 crimped or rolled seam. The bottom head C of the can has a countersink C' and seaming-flange c, which is united to the lower end of the can-body by a seam a', this being also preferably a rolled or crimped seam, although 75 any other suitable form of seam may be employed. The annular can-top B, in addition to the depending or downwardly-projecting annular flange b, is furnished with an outer marginal channel or groove b² and with an 80 outer depending or downwardly-projecting flange b³ and with a horizontal flange b⁴, said flanges b³ b⁴ forming an annular depending flange b.

D is an annular friction-fit irremovable 85 sheet-metal ring having a horizontal flange d, the outer edge or rim of which is adapted to rest snugly against and tightly engage the annular flange b³ of the top B and form a tight snug fit therewith. The ring D has a depending flange or portion d', the outer face of which is adapted to tightly fit and snugly engage the inner face of the depending flange b of the can-top B when the ring D is forced under great pressure into the can-top B, this 95 being ordinarily done after the can is filled in the same manner that the ordinary friction-cover is forced into the ordinary friction-top can to close the same; but the friction-fit ring D is thus irremovably secured to the can-top 100 B, as its horizontal flange d fits snugly within the annular flange b³ of the can-top, so that no leverage or other means is afforded for removing or prying off the friction-fit frangible-

seal-carrying ring D. The inner face of the depending flange or portion d' of the ring D constitutes the friction-face, which engages the removable sheet-metal cover F, and this 5 friction-face, which is substantially upright, is preferably very slightly inclined or wedging. The frangible seal E is preferably of paper or other easily breakable or severable material and is fixedly secured to the ring D, 10 this being preferably done by an annular integral fold d^2 , formed in the ring D, and which fold when turned or pressed down flat, as illustrated in Figs. 1 and 4, engages and 15 clamps the frangible seal E at its rim or marginal portion, and thus firmly secures the frangible seal in its bearing or carrying ring D. The frangible seal or carrying-ring D is 20 preferably furnished with a marginal fold d^4 at its extreme inner edge to give a smooth-edged opening into the can when the frangible seal is cut out or removed.

The friction cap or cover F has a somewhat deep countersink F' therein, forming a depending annular flange f nearly upright, but 25 preferably slightly wedging or inclined, and the outer face f' of which constitutes the friction-face of the cover that engages the corresponding friction-face d^5 of the annular depending flange d' of the ring D, thus forming 30 a liquid-tight closure between said cap or cover F and the frangible-seal-bearing ring D when the cap or cover F is forcibly pressed home in said ring D. The friction cap or cover F is provided with a folded flange f^2 at 35 its rim to strengthen and stiffen the same and give it a smooth edge or rim. The folded flange f^2 at the rim of the cover F also affords a shoulder for engagement with a lever or tool used in prying off the cover for 40 opening the can.

At the can-factory where the cans are manufactured the frangible seal E is first clamped and fixedly secured to its carrying-ring D. After the can is filled this ring D is driven or forced under great pressure into the can-top B and these two parts so tightly and firmly secured together that they cannot afterward be separated and forming a liquid-tight joint by the extremely tight fit between the two 50 and connecting the same. The friction cover or cap F is then very tightly forced into the frangible-seal-carrying ring D, thus forming a liquid-tight joint between the two by the close tight elastic grip between the friction or 55 interengaging faces f' d^5 of the flanges f d' , and as the elastic gripping or friction faces of the cover F and ring D are slightly wedging or inclined the act of forcing the cover F into the ring D operates very firmly to clamp 60 the ring D between the cover F and the can-top B, thus giving still further security and tightness to both the joint between the ring D and top B and to the joint between the cover F and ring D. The intermediate ring D in a 65 sense acts somewhat as a packing between the

somewhat elastic depending flange f of the cover F and produces a closure which is exceedingly tight, safe, and reliable. The customer or packer in closing or sealing our improved can thus has two friction-closure operations to perform — first, that of seating the friction-closure frangible-seal-bearing ring D in place in the can-top B and then the seating of the friction-cover F within the ring D; but both these operations or closures are very 75 simply and easily performed. Our improved can thus has a double-friction closure.

If desired, the parts D, E, and F may be assembled at the can-factory, so that the packer or customer after the can has been filled may 80 close or seal it by simply pressing or forcing the assembled parts D, E, and F within the can-top B in the same manner as is done in the ordinary friction-top-can closure. In our invention also the parts B, D, E, and F may, 85 if desired, be all assembled together at the can-factory and the part B seamed to the can-body A after the can is filled, or, if preferred, the part B may be secured to the can at the factory and the can filled through its lower 90 end, the bottom head C in such case being seamed to the can-body after the can is filled. We, however, prefer to practice our invention in the manner first described and wherein both the friction-fit ring D and the friction-cover 95 F are applied after the can is filled.

When the purchaser or user desires to open the can, this is done by simply prying off the friction cap or cover F, as is customary in cans of the kind to which our invention relates. After the cover F is thus removed the frangible seal E, which is preferably of paper, may then be removed by breaking, tearing, or cutting it out. As the frangible seal E 100 cannot be replaced after being once cut out or broken, the can is incapable of use a second time without detection by refilling it with spurious goods, thus affording ample protection to the original packer of the can against fraud.

The frangible paper seal E may have printed thereon the name or trade-mark E' of the packer whose goods are in the can.

To more firmly secure the frangible seal in place after being clamped between its carrying-ring D and the clamping-fold d^2 , we preferably form holding teats or projections d^6 in the ring D.

We claim—

1. The non-refillable friction-top can herein shown and described, and comprising, in combination, a body A, a top or head B seamed to said body, and having a depending annular flange b , downward flange b^3 and horizontal flange b^4 , a frangible-seal-carrying irremovable friction-fit ring D, having horizontal flange d , and annular depending friction-fit flange or wall d' , and provided with an integral fold d^2 , a frangible seal embraced by said integral fold in said ring D, and a friction

cap or cover F having a friction flange or wall f engaging the flange or wall d' of said ring D, substantially as specified.

2. In a friction-top can, the combination with the can-body, of an annular can top or head having a large opening therein surrounded by a depending flange, a frangible-seal-carrying irremovable friction-fit ring fitting within said annular can top or head, and provided with a fold embracing a frangible seal, and a friction cap or cover fitting within said ring carrying said frangible seal, substantially as specified.

3. In a friction-top can, the combination with the can-body, of an annular can top or head having a large opening therein surrounded by a depending flange, a frangible-seal-carrying friction-fit ring fitting within said annular can top or head, and provided with a fold embracing a frangible seal, a frangible seal and a friction cap or cover fitting within said ring carrying said frangible seal, said frangible-seal-carrying ring having teats or projections to lock the frangible seal in its carrying-ring, substantially as specified.

4. In a friction-top can, the combination with a can top or head having a large opening therein and a flange surrounding said opening, of a frangible-seal-carrying irremovable friction-fit ring having a depending flange snugly fitting said flange of the can-top, and a frangible seal fixedly secured to said ring, substantially as specified.

5. In a friction-top can, the combination with a can top or head having a large opening therein and a flange surrounding said opening, of a frangible-seal-carrying friction-fit ring having a depending flange snugly fitting said flange of the can-top, a frangible seal fixedly secured to said ring, and a friction cap or cover fitting within said frangi-

ble-seal-carrying ring, substantially as specified.

6. In a friction-top can, the combination with a can top or head having a large opening therein and a flange surrounding said opening, of a frangible-seal-carrying ring having a depending flange snugly fitting said flange of the can-top, a frangible seal fixedly secured to said ring, a friction cap or cover fitting within said frangible-seal-carrying ring, said frangible-seal-carrying ring having an integral fold therein embracing the frangible seal, substantially as specified.

7. A friction-top can having a double friction closure, and comprising a can-top, a friction-ring fitting therein and carrying a seal, and a friction-cover fitting within said ring, both said ring and cover being adapted to be applied to the can after the same is filled, substantially as specified.

8. In a friction-top can having a friction-cover and a friction-ring adapted to be secured thereto after the can is filled, the combination with a can top or head having a large opening therein and a flange surrounding said opening, of a frangible-seal-carrying ring having a depending flange snugly fitting said flange of the can-top, a frangible seal fixedly secured to said ring, a friction cap or cover fitting within said frangible-seal-carrying ring, said frangible-seal-carrying ring having an integral fold therein embracing the frangible seal and provided with teats or projections to lock the frangible seal in its carrying-ring, substantially as specified.
